UNITED STATES PATENT OFFICE.

EDWARD A. ECKERT, OF CINCINNATI, OHIO.

TELEPHONE SYSTEM AND APPARATUS.

SPECIFICATION forming part of Letters Patent No. 249,164, dated November 8, 1881.

Application filed June 25, 1881. (No model.)

To all whom it may concern:

Be it known that I, EDWARD A. ECKERT, of Cincinnati, Hamilton county, Ohio, have invented certain new and useful Improvements 5 in Telephone-Exchange Systems and Apparatus, of which the following is a specification.

The entire operating system of a telephone-exchange, no matter how scattered the branch exchanges may be, should be under the effective 10 supervision of a chief operator. The operating system in each branch exchange should be under the effective supervision of sub-chiefs who have charge of the branch operating-rooms. The chief operator may manage one 15 of the local rooms himself and transact all his business as chief from his station as sub-chief as well as chief. A sub-chief should be able to hear at any time he wishes all that his operators are saying without interrupting them 20 in their work and without their knowledge, and the chief operator should be able to transmit his orders to his sub-chiefs without the intervention of the operators. These things are suggested because experience shows that there- 25 by the operators are kept under constant surveillance and control, and orders regarding them transmitted by their superiors without their knowledge.

My invention relates to telephonic circuits 30 arranged with an exchange for the use of the operator in charge of the exchange, and to circuits arranged in the general system among the branches for the use of the chief operator, who has charge of all the operating business.

35 Figure 1 is a plan of an exchange showing circuits, &c. We assume this to be the main exchange, or the one in which the chief operator is placed. Branch exchanges would be very much similar. Fig. 2 is a plan of an ex- 40 change system having four exchanges which are supposed to be connected by trunk-lines, as usual. Fig. 3 is an end view of a chief's or sub-chief's desk, and Fig. 4 a front view of the same.

45 Fig. 1 represents an exchange. 1 represents groups of line-wires coming from subscribers' stations; 2, the table of the operators having charge of the groups of lines. There are three of these operators' tables shown, lettered A, B, 50 and C. At the C table I show the general arrangement of circuits, the other tables being

similar. 8 is the desk of the operator in charge of the room and of the entire operating system, including any outlying branch exchanges.

In Fig. 2, 28 28 28 are outlying branch exchanges, named in the drawings "Brighton," "Fulton," and "Lynn." 32 is the main exchange, at which is located the chief operator, each of the branches being in charge of a sub-chief. The exchanges may be connected with trunk- 55 lines, as usual, for the transaction of the regular business of connecting subscribers.

In Fig. 1, upon table C, the ordinary table-circuits are shown. The operator at this and all other tables is provided with a generator, 65 4, or device for supplying signaling-currents; a telephone, 3, for conversation; a wedge or plug, 5, or equivalent device, for connecting with any of the lines; and a switch, 6, for throwing to the working-circuits either the 70 signaling or conversing apparatus. The general arrangement of these table-circuits may be varied considerably and made to conform to any of the prevailing systems of operating.

At the chief's desk, 8, is placed a generator, 75 10, a telephone, 9, a series of annunciators, 19, and a series of switches, 20, by which the annunciator-lines may be put to the generator or the telephone. At each operating-table is placed an annunciator, 13, having a switch, 14, 80 by which it may be put to the generator-circuit or the telephone-circuit. The annunciators 13 of the tables are connected to the annunciators 19 on the chief's desk by the lines 12. In this manner the chief has an annunciator for each table, a line running to the table, and each table has a chief annunciator. We will follow the circuit of one of these lines in detail. From the table ground 7 to the table-switch 14, thence through annunciator 13 85 to line 12, thence through proper annunciator on chief's desk to switch 20, thence to ground 11 at chief's desk. Such is the course of the circuit when the switches 14 and 20 are in normal position, as shown in the drawings. 90 If the chief turns switch 20 to the right, he sends signal-current from generator-wire 25 in an obvious manner and affects the annunciator 13 on the table called. The operator, turning his switch 14 down, connects his generator-wire 26, and sends signal-current in answer. 95 Both now turn switches the opposite way and

converse, the table-telephone being connected through wire 27, and the chief's desk-telephone through wire 24. The method of including a battery-transmitter in the telephone-circuits is obvious.

At the tables is a socket, 15, or equivalent connection-receiver, by which the operator may cord the line 12 to any of his outgoing lines the same as he would connect any two outgoing lines, and at the chief's desk similar connection-receivers, 22, are arranged, so that the chief may connect any two of his desk lines. The chief's desk-lines are not confined to connections with his tables. Lines 21 run outside his office and connect him with subordinates generally.

In Fig. 2, 32 is the main city exchange, and 31 the location therein of the chief. His desk-lines 12 run to the desks of the sub-chiefs in charge of the branch exchanges 28. The lines 29 run to sundry subordinates, such as inspectors, repairers, store-keeper, batteryman, time-keeper, roofman, &c., and to general manager's office. These terminals are represented as in rooms. (Marked 30.) At the branches in Fig. 2 the sub-chiefs have desk-lines 12 to their tables and lines 21 to their chief, and they may have such other lines as they need. It will be seen that the chief and sub-chiefs can communicate with their subordinates by simple operations of a switch. As terminal devices for these desk-lines I in practice make use of the drop invented by J. W. See, and described by him in Letters Patent No. 235,056, dated November 30, 1880, to which drop, however, I do not wish to confine myself in future operations with my invention.

I now come to another feature of the invention, by which a chief or sub-chief may overhear any operator in his work by simply pressing a switch.

In Fig. 1, 18 is a strip upon the chief's desk, grounded through the chief's telephone, as shown. Over this strip are switch-buttons 17, which form terminals for lines 16 going to the operators' tables. These lines are private to the chief, and the operator can make no use of them. Being open at the chief's desk, their use must originate with the chief. The lines 16 going to the tables connect with the table telephone line 27, as shown. If an operator be talking with a subscriber or another operator, the chief may, by pressing the proper button, bring his telephone into the private-branch circuit and overhear the parties without their knowledge.

Instead of the buttons 17, other forms of switches may be used without departing from the spirit of my invention.

A modification of the devices, &c., intended to combine the functions of the lines 12 and 16 in one line, and to arrange the lines con-

necting the chief and the sub-chief's desk in a single circuit, with simple drop devices in such circuit, is reserved as the subject of another patent.

Figs. 3 and 4 need little description. They show a convenient form of chief's desk, 19, 20, and 22 being the elements of annunciator-drops arranged upon the desk, 18 being the buttons for the private lines 16, while 34 and 35 represent the usual transmitting devices. If no batteries or motors are used for generating the signal-current, a treadle or hand-generator may be attached to the desk, or a special signal-battery may be inclosed in it to form the generator. While I show the main lines distributed among table-operators, it is obvious that operators' stations in a massed system would be the same in applying this invention.

I claim as my invention—

1. In a telephone exchange system in which the incoming lines are grouped upon contiguous operating-tables, the combination, with such tables, of a chief's desk having an independent line to each of said tables, and connections, substantially as described, whereby said chief's desk may form a terminal station upon any one of said independent lines or incoming line, or an intermediate station between any two of said operating-tables, any two of the incoming lines, or any one of said lines and tables, substantially as set forth.

2. In a telephone-exchange system in which is involved one or more operators' telephone-circuits, the combination, with such operators' telephone-circuits, of a chief's apparatus having a telephone and a private listening-line permanently connected with the operators' telephone-circuits, whereby at said chief's apparatus private cognizance may be had of the workings of said operators' telephones, substantially as set forth.

3. In a telephone-exchange system in which the service-lines focus to branch exchanges at which the focusing-lines are grouped upon contiguous operating-tables, the combination, with said operating-tables, of a sub-table in each branch exchange, forming the focus for lines from each table in such branch exchange, and an auxiliary central exchange, of which said sub-tables form the outlying stations, whereby said central exchange may form the terminal of a line leading to any sub-table in the entire system, any operating-table in the entire system, or any patron in the entire system, or an intermediate station between any two points of communication in the entire system, substantially as set forth.

EDWARD A. ECKERT.
